RAILROAD TIE

Berardino Gизzi, Wilmerding, Pa.

Application November 26, 1940, Serial No. 367,272

1 Claim. (Cl. 238—7)

This invention relates to railroad ties, and it is one object of the invention to provide a tie associated with a concrete foundation, the foundation resting upon a roadbed of conventional formation and the tie being so anchored to the foundation that it will be firmly held in place and prevented from moving out of its proper position.

Another object of the invention is to provide a tie so associated with the foundation that the tie may be bound to the foundation by a mass of poured concrete which not only covers the tie but also enters sockets in the foundation in which portions of the tie are engaged and causes the tie to be held against shifting vertically or horizontally when the concrete sets and hardens.

Another object of the invention is to provide the tie with improved means for engaging rails and firmly holding the rails against movement relative to the tie.

Another object of the invention is to permit removal of the tread and web portion of a rail when it becomes worn without disturbing the base portion of the rail or the members for securing the rail to the tie.

Another object of the invention is to provide a tie which is simple in construction, very strong and durable, and cheap to manufacture.

The invention is illustrated in the accompanying drawings, wherein

Figure 1 is a top plan view of the foundation to which the improved ties are applied when in use.

Figure 2 is a view showing ties applied to the foundation with rails mounted upon the ties.

Figure 3 is an enlarged sectional view taken transversely through Figure 4 upon the line 3—3.

Figure 4 is a top plan view with portions of the rails in section.

Figure 5 is a top plan view of one of the ties.

Figure 6 is a sectional view taken along the line 6—6 of Figure 5.

Figure 7 is a perspective view showing one of the rails with its elements separated.

Figure 8 is a perspective view of the tie.

Figure 9 is an enlarged perspective view of one of the wedges used for holding the rails upon the ties.

The foundation, which is indicated in general by the numeral 1, is formed of concrete and when formed is poured upon the roadbed in forms where it is allowed to set and harden, the forms being then removed. The foundation is of such width that its side portions project from the ties, as shown in Figure 2 and also in Figures 55

3 and 4. At points spaced from each other longitudinally of the foundation, there are provided pockets 2 which are arranged in pairs and since the pockets of each pair are located adjacent 5 opposite side edges of the foundation, the ties 3 may be set in place upon the foundation between the companion pockets and held in proper spaced relation to each other.

The ties 3 are of duplicate construction and 10 each is formed of strong metal and has end portions 4 connected by a bridging bar 5. The end portions 4 constitute chairs for the rails 6 and are formed with bolt-receiving openings 7, the outer end portions of the chairs 4 being bent downwardly to form depending flanges 8 which engage in the pockets 2, as shown in Figures 3 and 4. By having the ties provided with depending flanges which engage in the pockets, the ties will be properly spaced from each other 15 longitudinally of the foundation and also firmly held in parallel relation to each other at right angles to the foundation when concrete is poured into the pockets and allowed to set and harden about the flanges. Bolts 9 are passed upwardly 20 through the openings 7 with their threaded end portions projecting upwardly to such an extent that the rails may be firmly held in place when nuts are applied to the bolts. Since the openings are square and the portions of the bolts 25 passing through them of similar shape, the bolts will be held against turning in the openings and the nuts 10 may be screwed tightly into place. In view of the fact that the ties have large end portions of greater length than the width of a rail base, a very good support will be provided 30 for the rails and the rails will be prevented from having direct contact with the foundation and damaging the foundation when subjected to pounding as a train moves along a track.

40 The rails 6 are of the construction shown in Figures 3, 4 and 7. Referring to these figures, it will be seen that each rail has upper and lower sections 11 and 12, the upper section being formed with a tread 13 and a short depending web 14 through which opening openings 15 are 45 formed. The lower section 12 is formed with a base 16 carrying upstanding flanges or web sections 17 between which the web 14 fits where it is secured by bolts 18 which pass through openings 19 formed in the flanges 17 and through the openings 15 formed in the web 14. By this 50 arrangement, the upper sections of the rails will be detachably secured to the lower sections and when the tread portions of the rails become worn, it is merely necessary to remove the bolts

18 and, after lifting the worn upper sections out of place, substitute new ones.

The rails rest upon the end portions 4 of the ties between the openings 7 from which they are spaced slightly and wedged 20 are then driven into place between the bolts and the side edges of the rail bases. These wedges fit under the washers 21 and are provided along their inner sides with inwardly extending flanges 22 which overlap the side edge portions of the rail bases 10 to hold the rails against upward movement. By employing the wedges, a tight gripping will be established at opposite sides of the rail bases and, in addition, pressure exerted by the tightened nuts 10 will be applied to upper faces of the side edge portions of the rail bases for an appreciable distance. Therefore, the rails will be very firmly held in place upon the end portions of the ties and prevented from working loose.

When rails are to be laid in accordance with this invention, the foundation 1 is first formed along the previously prepared roadbed, and after the concrete foundation has set and hardened, the ties are set in place with their depending flanges 8 engaging in the pockets 2 of the foundation. The bolts 9 are passed upwardly through the openings 7 before the ties are set in place, and since their heads are countersunk, the ties will have flat contacting engagement with the upper face or surface of the foundation. The rails are then set in place upon the end portions 4 of the ties and after they have been trued to extend in parallel spaced relation to each other, the wedges are driven tightly into place under the washers 21 between the bolts and side edges of the rail bases, the nuts 10 being then tightened to apply pressure and firmly hold the wedges in tight gripping engagement with upper faces of the rail bases. The nuts for the bolts 18 are tightened so that the upper sections of the rails will be firmly held and concrete 22 then poured upon the foundation in covering relation to the ties. This concrete is heaped against opposite side faces of the rails and completely covers the bolts 9 and their nuts and also the bolts 18 which pass through the web portions of the rails. It should be noted, however, that the concrete terminates slightly below upper edges of the flanges

or web sections 17 so that it is spaced downwardly from the treads of the rails. Therefore, when the tread portions of the rails become worn, portions of the set concrete 22 covering the bolts 5 18 can be broken away to expose these bolts and the bolts easily withdrawn after their securing nuts have been removed. The worn upper sections of the rails can then be lifted out of place and new ones substituted, the bolts being then 10 replaced and tightened or new ones used and concrete or a cement mixture employed to cover the bolts. In view of the fact that portions 23 of the concrete 22 will fill the pockets 2 about the depending flanges 8 of the ties, the ties will 15 be firmly held in place after the concrete sets and be prevented from moving out of their proper positions longitudinally or transversely of the foundation and also held against vertical movement.

I have, therefore, provided an improved construction wherein ties of an improved form are very firmly mounted upon a concrete foundation and rails so secured that they will be firmly held in place upon the ties but their upper portions 20 permitted to be easily removed when necessary and new ones substituted.

Having thus described the invention, what is 25 claimed as new is:

In a track structure, a continuous longitudinally extending concrete foundation of a width corresponding to the width of the track and formed with pockets opening through its upper face and located adjacent opposite side edges of the foundation in spaced relation to each other longitudinally 30 of the foundation, metal ties extending transversely across the foundation and resting flat against the upper surface of the foundation, said ties having wide end portions constituting rail chairs and bent downwardly at their ends to form depending flanges engaged in the pockets, the 35 pockets being of appreciably greater depth and greater length and width than the flanges to provide space in the pockets about and under the flanges adapted to be filled with concrete for 40 securing the flanges in the pockets and firmly holding the ties in place on the foundation.

BERARDINO GIZZI.
